PISTON EXPANDING DEVICE

George C. Mayfield, Richmond Heights, Mo., assignor to McQuay-Norris Manufacturing Company, St. Louis, Mo., a corporation of Delaware

Application October 7, 1948, Serial No. 53,305

5 Claims. (Cl. 153—80)

1

This invention pertains to expanders, such as are used to enlarge the diameters of pistons for internal-combustion engines to fit the piston to the cylinder. Such pistons are often heat-treated in their expanded condition, so as to set the metal permanently in its new shape.

One of the objects of this invention is to provide an expander which may be operated to expand the piston skirt at either its upper or its lower end, or both.

Another object is to provide such an expander of novel construction, which shall be rugged, but easily manipulated.

Another object is to provide such an expander with a novel type of expanding element.

Another object is to so construct the device that the same expanding element may be manipulated to expand the upper or the lower portion of the piston, or both.

Further objects will appear from the following description, taken in connection with the accompanying drawing, in which will be set forth an illustrative embodiment of the invention. It is understood, however, that this invention is susceptible of various embodiments, within the scope of the appended claims, without departing from the principle or spirit of the invention.

In the accompanying drawing:

Figure 1 is a side view, with parts broken away, of an expander embodying this invention, shown as applied to a piston, the latter partly in section;

Figure 2 is a section on line 2—2 of Figure 1;

Figure 3 is a fragmentary view, similar to Figure 1, showing the application to a modified type of piston;

Figure 4 is an enlarged detail of the expander chain;

Figure 5 is a side view of a length of the expander chain, illustrating a certain degree of flexibility; and

Figure 6 is a partial section on line 6—6 of Figure 1.

In accordance with this invention, generally stated, an expander element in the form of a chain having special properties is anchored so as to be adjustable in length between anchorages. Said anchorages are then mounted for movement such as to cause the expander element to move laterally at either end portion, or simultaneously at both end portions. This assembly, when placed inside a piston skirt, may then be manipulated to expand the skirt as desired.

Referring now to the drawing, 1 designates gen-

erally a supporting body on which the other parts of the assembly may be carried. The body 1 includes a base 2, a pair of side plates 3 mounted on the base 2 by screws 4 and dowels 5, and an expandable head 6. Threaded through the base 2 is an operating element 7 in the form of a sleeve, which is connected to the head 6 as will be more fully described hereinafter. Extending through the sleeve 7 is another operating element 8. This latter element comprises an internally threaded sleeve, engaging a correspondingly threaded rod 9 having an enlargement 10 bored out to fit over the piston-pin 11 of the piston 12, which is to be expanded.

15 The expanding element is in the form of a chain 13. In the embodiment illustrated, this is in the form of a sprocket chain of the silent type, such as is used for timing chains in internal-combustion engines. Such chains have the special property that the pivots between the links are designed to permit only a limited pivotal movement. This makes the chain stiff, so that it will not bend in an arc of less than a certain minimum radius in one direction, and usually will bend only very slightly in the opposite direction. This is illustrated in Figure 4, in which the dotted positions of the right-hand link indicate the maximum flexure in opposite directions. The stiffness in the "backward" direction is illustrated in Figure 5, in which the deflection d at the middle of a span of fourteen $\frac{3}{8}$ " links is $\frac{1}{16}$ " to $\frac{1}{32}$ ".

On account of the limited pivotal movement, such a chain has the property that, when bent to a given radius, end thrust on the chain will cause it to bulge laterally with respect to the direction of thrust, by virtue of a toggle action between links, which is transmitted from link-to-link along the chain. Accordingly, for the purposes of this specification and the appended claims, such 40 a chain will be termed a "toggle-chain," by which is meant a series of thrust links pivoted serially end-to-end, so that endwise pressure on the chain will cause the links to bulge with a toggle action, exerting a thrust in a direction transverse to said 45 endwise pressure.

A pair of chains 13 is connected to an upper anchorage plate 14, threaded to an extension 15 of the rod 9 above the enlargement 10. The lower ends of the chains 13 are adjustably connected to 50 the expandable head 6. This head comprises several parts. A carrier block 16 having laterally extending guide ribs 17 has a swivel connection to the operating element 7. This swivel connec-

tion is formed by a pair of blocks 18 secured to the underside of the block 16, and provided with inner ribs 19 engaging a groove 20 in the operating element 7. This connection provides that, when the element 7 is turned in the base 2, its threads cause it to move endwise in that base, thereby moving the head 6 toward or away from said base 2.

Mounted to slide on the ribs 17 are two slide blocks 21, each provided with oppositely projecting pins 22. The pins 22 engage in cam slots 23 in the side plates 3, so that, when the head 6 is moved toward or from the base 2, the slide blocks 21 will be moved outward or inward by the cam action of said pins and slots. Each slide block 21 is formed with a wedge-shaped tooth 24 adapted to be engaged by the sprocket-teeth of one of the chains 13. The chain is secured in such engagement by a pair of keeper plates 25, fitting into slots in the slide block 21, and secured by set screws 26 or the like. Each of the plates 25 is provided with grooves 27 adapted to receive the heads of the pivot pins of adjacent links of the chain.

By removal of one of the plates 25 on each of the respective slide blocks 21, the position of engagement along the chains 13 may be shifted to adapt the expander to pistons of widely differing skirt lengths. In this way, variation is made in the number of chain links between the anchorage plate 14 and the connection with head 6; the surplus chain depending below the latter connection as shown at 28.

The rod 9 passes freely through a central bore in the carrier block 16, while the end of the sleeve 8 may abut against the lower face of said block to support the upward pull of the rod 9. A nut 29 may be positioned on the rod 9 to limit its movement in the block 16.

In the use of this device, the chains 13 are secured to the head 6 as described, their length being adjusted to suit the piston to be expanded. The expander is then inserted into the piston as shown in Figure 1, and the piston pin 11 may be inserted into its bearings in the piston, passing through the bore of the enlargement 10. The operating element 8 may now be turned on the threaded rod 9 to draw the anchorage plate 14 downward toward the head 6. This causes the chains 13 to bulge in the region of the upper portion of the skirt by the toggle action explained above. The element 8 is turned until the outward thrust of the bulging chains expands the upper portion of the skirt the desired amount. If only the top of the skirt is to be expanded, the manipulation may stop here. If the lower portion of the skirt only is to be expanded, the chains may be bulged just sufficiently to contact the skirt, and then the head 6 may be expanded by operation of the element 7 until the skirt shows the desired expansion. It is often desirable to make the diameters of the upper and lower portions of the skirt different by a slight amount. In such a case, the chains may be bulged until they just start to expand the skirt, and then the head 6 adjusted to the desired difference in diameter, after which both operative elements 7 and 8 may be operated in unison to expand both upper and lower portions of the skirt simultaneously. The elements 7 and 8 are provided with adjacent knurled manipulating heads, as shown in Figure 1, so that both may be grasped simultaneously and operated in unison. When the desired expansion has been obtained, the expander, with the piston on it, may be placed in

any suitable heat-treating means whereby the expanded shape of the piston may be rendered permanent.

In Figure 3, a piston having an internal rib 30 is shown. In such a case the backward flexibility illustrated in Figure 5 makes it possible to exert full pressure on the piston at the bulge of the chains without excessive pressure on the rib 30.

10 It will be seen, therefore, that this invention provides an expander adaptable to almost any condition under which pistons are ordinarily expanded. The action of the toggle-chain is such that adequate lateral thrust can be applied to the piston, though the chain is flexible enough to accommodate itself to different sizes of pistons. The manipulation of the chain and the expandable head 6 may be such as to control the expanded shape of the piston to a high degree of 15 precision, both as to actual dimensions and as to relative sizes of different parts of the skirt.

Having thus described the invention, what is claimed and desired to be secured by Letters Patent is:

25 1. An expander of the character described, comprising, upper and lower anchorages, a toggle chain connected to each of said anchorages, means for moving said anchorages rectilinearly relative to each other, one of said anchorages 30 being expandable transversely of the direction of said rectilinear relative movement, and means for expanding said latter anchorage.

2. An expander of the character described, comprising, a supporting body having an expandable portion, an extensible element on said body, a pair of toggle-chains connected to said element and to the expandable portion of said body, means for moving said element and said body relatively to decrease and increase the rectilinear 35 distance between the chain connections and thereby to bulge or shrink said chains, and means for expanding said expandable portion of said body.

3. An expander of the character described, comprising, a supporting body having an expandable portion, an extensible element on said body, a pair of toggle-chains connected to said element and to the expandable portion of said body, means for moving said element and said body relatively to decrease and increase the rectilinear distance 40 between the chain connections and thereby to bulge or shrink said chains, and means for expanding said expandable portion of said body, said moving and expanding means being operable separately for producing said bulging and expanding adjustments separately, and in unison for producing said adjustments simultaneously.

4. A piston expander having a part for interlocking with the piston to be expanded, a pair of anchorages adjacent said part, a pair of toggle-chains anchored one to each anchorage, a body member having an anchorage at each side thereof for connection respectively with said chains, means for spreading apart the anchorages on the body member to vary the distance between the ends of different chains connected thereto, and means for moving said body toward and away from said part to vary the distance between the anchored portions of the same chain and thereby to bow or flatten the portion 55 of the chains between anchorages.

5. An expander of the character described, comprising, a supporting body, a toggle-chain, an element in threaded engagement with said body and connected to said toggle-chain at its 60 end remote from said body, said body having an

expandable portion, a second element in threaded engagement with said body and operable to expand said portion thereof, and an adjustable connection between said chain and said expandable portion of said body, said elements being rotatable relative to said body either separately or in unison.
